WAVE GUIDE ATTENUATOR

Arnold E. Bowen, Red Bank, N. J., assignor to
 Bell Telephone Laboratories, Incorporated, New
 York, N. Y., a corporation of New York

Application May 7, 1943, Serial No. 486,013

21 Claims. (Cl. 178—44)

1

This invention relates to wave transmission network and more particularly to an attenuator for guided electromagnetic waves.

An object of the invention is to attenuate guided electromagnetic waves.

Another object is to provide a wave guide attenuator which may be continuously varied from zero to any chosen upper limit of attenuation.

In transmission systems employing an air-filled metallic pipe as a guide for electromagnetic waves it is often desired to introduce a known amount of attenuation. It is convenient to be able to vary the attenuation continuously from zero to the required upper limit.

The present invention provides a wave guide attenuator which is continuously variable from zero to any desired maximum value. The attenuator comprises a section of metallic pipe wave guide within which is longitudinally positioned a resistive septum. To make the attenuator variable, means are provided for moving the septum sidewise and thereby varying the separation between the septum and a side of the wave guide. In the embodiment disclosed the guide is of rectangular cross-section and the septum is parallel to a side of the section.

The nature of the invention will be more fully understood from the following detailed description and by reference to the accompanying drawings in which:

Fig. 1 is a perspective view of a wave guide attenuator in accordance with the invention;

Fig. 2 is a plan view, partly in section, of the attenuator of Fig. 1; and

Fig. 3 is a perspective view of the resistive septum used in the attenuator shown in Figs. 1 and 2.

As shown in perspective in Fig. 1 and in plan in Fig. 2, the attenuator comprises a section of metallic pipe wave guide 1 of rectangular cross-section, a resistive septum 2 positioned within the section 1 substantially parallel to the shorter dimensioned side 3 of the section 1 and means for moving the septum 2 either toward or away from the side 3. Each end of the section 1 is provided with a flange 4 for connecting the attenuator to an adjacent section of wave guide. The flange 4 may be provided with aligning pins 5 which fit into holes such as 6 in a flange on the end of the adjacent section of guide. The section 1 is made of a metal or an alloy having good electrical conductivity such, for example, as brass, and is preferably plated on the inside with precious metal such, for example, as silver or platinum.

2

The septum 2 is moved by means of a rod 7, to the inner end of which the septum 2 is fastened by a screw 8 which passes through a central hole in the septum 2 and screws into a tapped hole in the end of the rod 7. The rod 7 and the screw 8 are made of suitable insulating material such, for example, as hard rubber. The rod 7 slides in a hole 9 in the lower block 10 and passes through a hole 11 in the side 3 of the guide section 1. The rod 7 is actuated by means of the rack 12, which is fastened to the rod 7, and the pinion gear 13. The pinion 13 is on the lower end of a shaft 14 which passes through a hole in the upper block 15 and is held in place by the pronged member 16 which is fastened at one end to the top of the block 15 and at the other end fits into an annular groove in the shaft 14. The upper block 15 is fastened to the lower block 10 by the screws 17 and the entire assembly is securely attached to the side 3 of the section 1.

The dial 18 and knob 19 are fastened to the upper end of the shaft 14 by the set screw 20 and a pointer or index 21, fastened to the section 1, is provided for reading the calibration on the dial 18, as shown at 22. The calibration 22 may conveniently be made directly in decibels.

As shown more clearly in the perspective view of Fig. 3, the septum 2 consists of a plate of suitable insulating material such, for example, as phenol fibre, coated on the face toward the side 3 with one or more layers of resistive material 23. The resistive material may, for example, be a mixture of finely divided graphite and a suitable binder, sprayed onto the side of the septum 2 in one or more coats. The ends of the septum 2 are preferably specially shaped to reduce the reflection effects when the section 1 is inserted into the wave guide system. As shown at 24 and 25 in Fig. 3, this special shaping may take the form of a rectangular notch, the optimum depth and width of which are best determined by trial. Other forms of special shaping may, however, be used. In order to minimize the variation in attenuation with frequency the central hole 26 in the septum 2 may be extended on each side in the longitudinal direction, as shown at 27 and 28. The optimum dimensions for these extensions are also best found by trial.

The amount of attenuation introduced by the attenuator depends primarily upon the length, width and thickness of the resistive coating 23 and the distance between the septum 2 and the side 3 of the section 1. When the septum 2 is in contact with the side 3 the attenuation is substantially zero. As the septum 2 is moved away from the

side 3 the attenuation increases in accordance with a smooth curve until a maximum is reached when the septum 2 has moved half-way or less across the section 1. The desired attenuation is obtained by turning the knob 19 which rotates the pinion gear 13 and, acting through the rack 12, pushes the rod 7 either in or out and thus determines the separation between the side 3 and the septum 2, which is fastened to the end of the rod 7. A maximum attenuation of as high as 40 decibels has been obtained with a variable attenuator of the type disclosed herein.

What is claimed is:

1. An attenuator comprising a section of metallic pipe wave guide and a resistive septum longitudinally positioned within said section and spaced from a side of said section, the ends of said septum being notched.

2. An attenuator in accordance with claim 1 in which the ends of said septum have rectangular notches.

3. An attenuator comprising a section of metallic pipe wave guide of rectangular cross-section and a resistive septum positioned within said section substantially parallel to, but separated from, a side of said section, the ends of said septum being notched.

4. An attenuator in accordance with claim 3 in which the ends of said septum have rectangular notches.

5. A variable attenuator comprising a section of metallic pipe wave guide, a resistive septum longitudinally positioned within said section and means for moving said septum laterally.

6. An attenuator in accordance with claim 5 in which the ends of said septum are notched.

7. An attenuator in accordance with claim 5 in which said septum comprises a plate of insulating material coated on a major face with resistive material.

8. A variable attenuator comprising a section of metallic pipe wave guide of rectangular cross-section, a resistive septum positioned within said section substantially parallel to a side of said section and means for moving said septum laterally.

9. An attenuator in accordance with claim 8 in which said septum comprises a plate of insulating material coated on a major face with resistive material.

10. An attenuator in accordance with claim 8 in which said section has unequal cross-sectional dimensions and said septum is substantially parallel to a side of said section having the shorter width dimension.

11. An attenuator in accordance with claim 8 in which said means permit moving said septum to a position of substantially zero attenuation.

12. An attenuator in accordance with claim 8 in which said means permit moving said septum from a position of substantially zero attenuation to a position of maximum attenuation.

13. An attenuator for use in a wave guide in which high frequency electric waves are propagated comprising a wave guide portion having a mode of propagation in which the maximum intensity electric vector lies in a flat plane symmetrically through and longitudinal of said guide portion, a thin, flat resistance member carried by said guide section and having an effective portion thereof lying in a plane parallel to the maxi-

mum intensity electric vector and means for moving said effective portion from a region of minimum electric field intensity to a region of maximum electric field intensity whereby a continuously variable degree of attenuation may be provided.

14. An attenuator in accordance with claim 5 in which one end of said septum is specially shaped to reduce reflection.

15. An attenuator in accordance with claim 8 in which one end of said septum is specially shaped to reduce reflection.

16. A variable attenuator comprising a section of metallic pipe wave guide, a resistive septum longitudinally positioned within said section and means for moving said septum laterally, in which the ends of said septum are specially shaped to reduce reflection.

17. A variable attenuator comprising a section of metallic pipe wave guide of rectangular cross-section, a resistive septum positioned within said section substantially parallel to a side of said section and means for moving said septum laterally, in which the ends of said septum are specially shaped to reduce reflection.

18. A variable attenuator comprising a section of metallic pipe wave guide of rectangular cross-section, a resistive septum positioned within said section substantially parallel to a side of said section and means for moving said septum laterally, in which said means permit moving said septum from a position adjacent to a side of said section to a position approximately half-way across said section.

19. An attenuator for a rectangular wave guide comprising a relatively thin plate of dielectric material carrying on at least one broad face thereof a loss-producing coating, said plate being mounted within said guide with its plane parallel with the electric field in said wave guide, and means at one end of said plate for matching the input impedance of said attenuator to the characteristic impedance of said wave guide.

20. An attenuator comprising a section of metallic pipe wave conductor, an elongated dielectric carrier longitudinally positioned within said section, a coating of resistive material on the main section of said carrier, and at least one end portion of said carrier having a resistive coating of a different resistance value per unit length of the carrier than the coating on said main section to reduce wave reflection in said conductor.

21. An attenuator comprising a section of metallic pipe wave conductor, an elongated dielectric carrier longitudinally positioned within said section, a coating of resistive material on the main section of said carrier, and at least one end portion of said carrier having a resistive coating specially shaped to reduce wave reflection in said conductor.
